UNITED STATES PATENT OFFICE.

ANGUS F. HANNEY, OF CHICAGO, ILLINOIS, ASSIGNOR TO EUREKA ROUGH DRY PIN SYSTEM CO., OF CHICAGO, ILLINOIS.

LAUNDRY-TAG CARRIER.

Original application filed August 2, 1920, Serial No. 400,850. Divided and this application filed September 3, 1921. Serial No. 498,371. Renewed October 31, 1923.

To all whom it may concern:

Be it known that I, ANGUS F. HANNEY, a citizen of the United States, and a resident of the city of Chicago, county of Cook, and 5 State of Illinois, have invented certain new and useful Improvements in Laundry-Tag Carriers, of which the following is a specification.

My invention relates to new and useful 10 improvements in laundry tag carriers, and has for its object the provision of means for carrying a group of laundry tags and for releasing said tags from articles to which they are attached.

15 Other objects will appear hereinafter.

This case is a division of applicant's prior application, Serial No. 400,850, filed August 2, 1920, which relates particularly to the 20 form of laundry tag with which my tag carrier is especially adapted to co-operate.

The invention consists in the combinations and arrangements of parts hereinafter described and claimed.

The invention will be best understood by 25 reference to the accompanying drawings forming a part of this specification, and in which,

30 Fig. 1 is a perspective view of my improved tag carrier illustrating the laundry tag in position thereon, both before and after removal from the laundered article,

Fig. 2 is an enlarged transverse section of the tag shown in position of attachment to an article, and

35 Fig. 3 is a similar sectional view showing the tag in position of detachment from the article.

The particular form of laundry tag for 40 which my carrier is especially adapted, which tag forms the subject matter of the parent case above referred to, comprises a hollow flat metallic body or casing 4 having a lip 5 projecting upwardly from the top thereof, said lip being adapted and arranged 45 to receive an identifying number or mark stamped therein. A pointed member 6 is secured in the casing 4 in position to project downwardly from one side thereof. Co-operating with the pointed member 6 is a locking lever 7 pivoted at 8 at the lower side of the tag and carrying a cuff or ring 9 at its free end adapted to fit over the pointed member 6, as shown in Fig. 2, to hold said tag in engagement with the article to be laun-

dered, as indicated by the dotted lines in 55 Fig. 1. The lever 7 is provided with a lug or projection 10 adapted to engage in a notch 11 in a spring held detent 12 pivoted at 13 in the casing 4. The casing 4 is provided with a transverse slot 14, and one end 60 of the detent 12 traverses the lower end of said slot, as shown in Figs. 2 and 3.

My improved carrier bar 15 is provided to carry the above described tags and to actuate said tags to release the articles carried thereby, and is arranged to pass through the slots 14 of the laundry tags, said bar being provided at its inner or supporting end with a stop lug 16 to facilitate releasable mounting of said bar on a suitable supporting 70 bracket. The bar 15 is also provided at its outer or receiving end with a similar stop lug 17 which prevents the accidental removal of the tags from the bar. The outer 75 end of the bar 15 is somewhat narrower than the inner end, a cam surface 18 being provided on the lower edge of the carrier bar at the junction of the narrower and broader portions of said bar, the junction of the two 80 portions thus providing means to actuate the tags to release the articles while the tags are slid along the bar. A removable transverse stop, in the form of a rod or pin 19, is arranged in the bar and rests loosely in a 85 transverse opening therein immediately above the cam surface 18.

In use, the carrier bar 15 is removably supported within a suitable bracket or support. The laundry tags, having laundered articles attached thereto, from which it is 90 desired to remove the same, are then placed in position on the outer end 17 of the bar 15 by passing the slots 14 of the tags over the outer end of the bar. When the desired 95 number of tags have thus been placed in position on the bar, and this number will usually be the number of tags attached to articles for a particular customer of the laundry, and the tags have been properly checked to show that all the articles belonging to that customer are present, the pin 19 is removed from the bar 15 and the tags pushed in a body inwardly onto the larger inner end of the bar, thus causing the cam surface 18 to engage the detents 12 of 100 the different laundry tags and to release the locking lever 7 of said tags and permit the 105 laundered articles to fall by gravity from

the tags, a suitable basket or receptacle being set to catch said articles. The tags may now be readily removed and retained in a group for one customer, this procedure tending to prevent mistakes and greatly aid orderly and efficient conduct of the laundry business.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:—

- 25 1. In combination with a laundry tag provided with means for carrying articles, a carrier bar having two portions varying in size, one of said portions being constructed to receive said tags while carrying articles, and the other to retain the tags in a group, and means on said bar at the junction of said portions to actuate the means on said tags and release the carried articles.
- 30 2. In combination with a laundry tag provided with means for carrying articles, of a carrier bar having one portion narrower than the other for receiving tags thereon, a cam surface on said bar at the junction of said portions for actuating the means on said tags to release articles carried thereby, and a pin removably mounted on said bar adjacent said cam surface to retain said tags on either portion of said bar.
- 35 3. In combination with a laundry tag provided with means for carrying articles, a carrier bar comprising a narrow portion for supporting said tags, a wide portion for receiving tags from said narrow portion and holding the tags together, the junction of said portions being constructed for actuating said means on said tags to release attached articles and means for supporting the bar for convenient detachment.
- 40 4. In combination with a laundry tag provided with means for carrying articles, a

carrier bar comprising a narrow portion for supporting tags attached to articles, a wide portion connected to said narrow portion and receiving tags therefrom, means for actuating the means on said tags to release said attached articles, means at the free end of said narrow portion for retaining said tags, and a supporting lug at the free end of said broad portion for supporting said bar.

5. In combination with a laundry tag provided with releasable means for carrying articles, a carrier bar comprising a narrow and a broad portion, said narrow portion being adapted to receive laundry tags carrying articles, a cam surface at the junction of said narrow and broad portions for actuating the means on said laundry tags to release said articles, while the tags are moved from the narrow to the broad portion, means on said bar for supporting same, and a retaining member removably mounted in said bar adjacent said cam for retaining said tags on either said narrow or broad portion.

6. In combination with a laundry tag provided with releasable means for carrying articles, a carrier bar for receiving laundry tags carrying articles, having two portions varying in cross sections, one portion being adapted to receive the tags with the articles, and the other to retain the released tags, and means on said bar at the junction of said portions to actuate said releasable means on said tags and release said articles therefrom.

7. In combination with a laundry tag provided with releasable means for carrying articles, a carrier bar for supporting laundry tags, a cam on said bar for releasing said means on said tags while moved over said bar, and a lug at one end of said bar for mounting the bar on a support for convenient dismounting thereof.

In testimony whereof I have signed my name to this specification in the presence of two subscribing witnesses.

ANGUS F. HANNEY.
